UNITED STATES PATENT OFFICE.

MATTHEW LAFLIN, OF CHICAGO, ILLINOIS.

IMPROVEMENT IN HARVESTERS.

Specification forming part of Letters Patent No. 128,638, dated July 2, 1872.

SPECIFICATION.

To all whom it may concern:

Be it known that I, MATTHEW LAFLIN, of Chicago, in the county of Cook and State of Illinois, have invented certain Improvements in Reapers and Mowers, of which the following is a specification, reference being had to the accompanying drawing.

My invention consists of certain improvements in reapers and mowers, whereby the height of its cut can be regulated at will; also, in certain other features of detail, hereinafter more fully described.

Figure 1 is a side elevation; Fig. 2, a longitudinal vertical section; and Fig. 3, a bottom-plan view of the seat with the devices for throwing the mechanism in and out of gear.

The machine I construct with a frame, A, mounted on two large wheels, one of which carries the driving-gear and operates a cam-wheel, D, which in turn operates a lever, I, that is connected by a pitman to the sickle, as described in a patent heretofore granted to L. B. Hoit and myself—these parts containing nothing new. The finger-bar is connected, by a drag-bar, G, to the end of the axle outside of the wheel, as shown in Fig. 1. In the front end of the shoe, which is slotted for the drag-bar G to pass through it, I pivot a cam or eccentric, H, so that as it is turned over back it will bear on top of bar G and thereby elevate the front end of the shoe, and thus raise the finger-bar and sickle. To operate this cam H, I pivot a lever, T, on the outer end of the axle, as shown in Fig. 1, and connect it, by a rod, P, with the cam, so that, by shoving the lever T back and forth, the shoe with the sickle can be raised or lowered at will, and without stopping the machine. To raise the sickle from the ground I use a lever, L, which is pivoted on the axle inside of the frame, and has a chain, m, passing from it around a pulley, p, on the rear of the frame, as shown in Fig. 1. To hold this lever in place, and prevent it from falling over back, out of the reach of the driver, I connect to its lower end a spiral spring, a, which has its opposite end attached to the rear end of the frame, as shown in Fig. 1. By this means the lever is always held in position where it can be readily grasped by

the driver, and is still loose to permit it to move with the movement of the finger-bar as it passes over the undulations of the ground. To support the cam-wheel D and the brace-rods that hold the shoe laterally, I use a metal frame, B, of L-form, as represented in Fig. 2, similar to that shown in the patent heretofore referred to; but I construct this frame with its inner upright arm of sufficient length to form a support for the seat, its upper end being suitably enlarged for that purpose. The seat is bolted securely upon this arm C, and its opposite end is supported by two braces, e, attached at their lower ends to the main frame A, as shown in Fig. 1. By this means I simplify and cheapen the construction, and render the parts very strong and secure. The cam-wheel, D, as stated, is supported between the upright arms C of the metal frame B; and as shown in Fig. 3, the pinion k, that communicates motion from the main wheel to the cam-wheel D, is mounted on the journal t of the latter, the cam-wheel being hollowed out on its end, so as to permit the hub to enter it; and on its inner end the hub of the pinion k has a couple of grooves or notches, s, formed longitudinally in its sides, a clutch, consisting of a ring, u, with two arms, r, projecting from its face, the ring being mounted loosely on the inner journal of the cam-wheel D, and the arms r sliding and resting in holes bored through the central hub of the wheel D. The ring u is provided externally with a circumferential groove, in which rests a yoke, v, to which a rod, n, is attached, the opposite end of this rod being connected to a lever, l, that is pivoted to the under side of the seat E, the front end of this lever l protruding at the front of the seat, as shown in Fig. 3. To the front under edge of the seat a bar, h, is secured, this bar being cut away so as to leave a space for the lever l to move back and forth in, and there being a notch cut in the bar near each end, in which a spring, o, fastened to the under side of the lever l engages, and thereby holds the pinion and cam-wheel in or out of connection, according as the lever is adjusted to one or the other side; and this being under the seat, is within easy reach of the driver.

It will be observed that by this construction

all the levers are brought within reach of the driver, and the machine, as a whole, is very simple and strong.

Having thus described my invention, what I claim is—

1. The shoe F, provided with the eccentric H, in combination with the bar G, arranged to operate substantially as described, whereby the shoe can be adjusted, as set forth.

2. In combination with the above, I claim the lever T and connecting-rod P, arranged to operate the eccentric or adjusting device, as set forth.

3. The metallic frame B, having its arm C, constructed as described, so as to serve as a support for one end of the seat.

4. The arrangement of the pinion k, wheel D, and clutch u with the lever l, pivoted to the under side of the seat, and connected to the clutch, as set forth.

MATTHEW LAFLIN.
